UNITED STATES PATENT OFFICE.

FELIX COUNE, OF CHICAGO, ILLINOIS.

HAIR-WAVING TUBE.

1,326,710.

Specification of Letters Patent. Patented Dec. 30, 1919.

Application filed June 19, 1917. Serial No. 175,552.

To all whom it may concern:

Be it known that I, FELIX COUNE, a citizen of the United States, residing at Chicago, in the county of Cook and State of Illinois, have invented new and useful Improvements in Hair-Waving Tubes, of which the following is a full, clear, concise, and exact description, reference being had to the accompanying drawing, forming a part 10 of this specification.

My invention relates to improvements in hair-waving tubes such as are used for the permanent waving of hair. There are various tubes of this kind now on the market, 15 but there are certain objections to these which my invention overcomes.

In the various processes of waving hair on the human head in which hair-waving tubes are used, the hair is first separated into 20 tresses and then the tresses are wound upon separate curlers. Each curled tress is then inserted into a tube which is secured around the tress adjacent the head, after which heat is applied to the tube to act upon the 25 enclosed composition, which in turn acts upon the curled tress of hair, effecting a so-called permanent wave thereof. It will be apparent that in working on a person's head in this manner, and especially where heat is applied so close to the scalp, every 30 precaution must be taken against hurting the person either by careless tying of the tube around the strand of hair or by the escape of steam from the head end of the tube. In the tubes now in use the outer tubular portion is made of a relatively stiff material. 35 This tube is secured around the tress adjacent the person's head, but, due to the structure of the tubes now in use, the tube is not always well sealed adjacent the head, with the result that steam will escape and sometimes burn the scalp. Furthermore, in tying the tubes now in use, the hair is sometimes pulled unevenly, thereby hurting the person 45 being operated upon and sometimes even breaking the hair at the head.

One of the features of my invention is the use of a relatively flexible sheet of non-absorbent material secured to the head end 50 of the tube, this sheet being preferably of a rubber cloth and so constructed that it may be tied around the tress of hair adjacent the head, thus forming a seal which will prevent the escape of steam or heat from the tube at the head end. Another advantage of using this construction at the head

end of the tube is that, due to its flexibility and resiliency, it may be readily tied or secured around the tress without injuring the person being operated upon. I also preferably place a thin sheet of tissue paper adjacent the rubber sheeting, so that the paper will lie between the layers of rubber and between the hair and the rubber, thus acting as an absorbent and an additional sealing 60 element. This paper will also prevent the hair from sticking to the rubber sheeting. With this improved construction the process of permanent waving is made much safer 65 than heretofore.

Another feature of my invention resides in the use of a combined cloth and paper inner tube or composition envelop, the paper portion lying next to the hair, while the cloth portion is rolled outside of the paper, a layer 70 of suitable composition being interposed between the paper and the cloth portions. With this construction I find that the cotton or gauze portion acts to absorb impurities in the composition and the paper acts as a 75 filter between the composition and the hair and does not turn white hair yellow, as has heretofore been done. This piece of paper also prevents the hair from coming in direct contact with the composition. I find that 80 by using this construction light-colored hair may be permanently waved without turning the shade.

Another advantage of my invention is having the cord secured to the flexible head 85 end of the tube, so that it cannot slip off the tube, and thus the tube may be more readily secured closer to the head of the person being operated upon.

For a better understanding of my invention, reference will be made to the accompanying drawing, in which—

Figure 1 is a perspective view of a blank 90 used for one form of the outer tube or casing;

Fig. 2 is a perspective view of the blank 95 used for the composition envelop or tube;

Fig. 3 shows the composition tube partially rolled up;

Fig. 4 shows one form of the tube fully 100 assembled;

Fig. 5 shows in perspective a blank for another form of outer tube or casing;

Fig. 6 shows the form of tube of Fig. 5 105 fully assembled; and

Fig. 7 is a longitudinal cross section of the tube as applied to a tress of hair.

Referring now more particularly to the preferred form of construction for the casing or outer tube, I provide a sheet of relatively stiff paper 1, paper about seven or 5 eight thousandths of an inch in thickness being suitable for this purpose. This sheet is preferably somewhat non-absorbent. At the head end 2 I provide a sheet of relatively flexible and resiliency non-absorbent material 10 3, preferably thin rubber sheeting, one form being slit at 4 so as to receive a cord 5 which is used for tying the finished tube around the hair which is to be waved. To prevent the rubber sheeting 3 from coming 15 in direct contact with the hair, I preferably provide a thin sheet of tissue paper 6 which is pasted outside the rubber sheeting 2, as shown in Fig. 1. It will be noted that the rubber tip 3 is cut away at 3^a, this being done 20 to permit the folding back of the extended portion 3^b when the tube is rolled, and is more clearly shown in Fig. 4.

The composition envelop or tube is preferably made out of a blank 7 of cotton gauze 25 having an end 8 preferably of an absorbent paper, but stiff enough to act as an inner tube to support the composition when the tube is rolled as shown in Fig. 3. In preparing the inner tube or composition envelop, any one of the well-known powder or 30 crystal compositions may be used, a thin layer being placed upon the upper side of the cotton sheet 7, after which the sides 9, 10 are folded over in a manner as indicated 35 in Fig. 3. To form the composition envelop a small wooden rod which acts as a former is laid upon the paper end 8 and this end 8 is then rolled around the rod and the rolling continued until the envelop takes 40 the form shown in Fig. 3. The free end of the portion 7 may then be pasted against the tube so as to hold it in place. The paper end 8 is preferably of such dimension that it may be rolled at least one convolution so 45 as to be interposed between the composition and the hair which is inserted into the tube.

To complete the tube the inner envelop or tube 7 is now placed upon the edge 1^a of the outer blank 1 and rolled up into the 50 form as shown in Fig. 4, the outer edge of the outer tube being then pasted against the tube so as to prevent the convolutions from spreading. The portion 3^b of the rubber tip or extension is then folded back so that the 55 cord 5 is in position to be tied as in Fig. 4.

Instead of passing the cord through slit- 60 tered portions of the flexible tip or extension, as shown in Figs. 1 and 4, the extension 3^b may be left whole, that is, not slit, and then folded back as shown in Figs. 5 and 6, the cord 5 being placed in position and the overlapping part 3^b pasted down at 12 so as to keep the cord from slipping off the end of the tube. This is shown also in 65 Fig. 7.

In the use of my improved tube for the permanent waving of hair, the hair is first separated into strands or tresses of suitable thickness and then wound around a metal or suitable curler. The outer end of the 70 tube is then dipped in water and partially immersed for from five to twelve seconds, according to the length of the tube and the quantity of composition in it. The tube is then placed over the curled tress, as shown 75 in Fig. 7, after which the flexible tip is securely tied around the tress as close to the head as possible. It will be apparent that, due to the use of the rubber tip, and by the method of securing the cord 5 thereto, the 80 tube is not only secured and sealed very close to the head of the person being operated upon, but the cord is prevented from slipping off the end of the tube. Also, because of the resiliency and flexibility of the 85 tip and the use of the thin paper liner 6, a more perfect seal is secured next to the head and thus there is less liability of steam or heat escaping to reach the scalp. This escaping steam in prior tubes has frequently 90 been the cause of serious injury. With my improved tip this is practically impossible. After the hair is inserted in the tube the open end of the tube is closed by inserting a wad of wool or cotton 11, thus preventing 95 the ready escape of heat or steam from the interior of the tube. Heat is then applied to the outside of the casing 1 by any of the well-known methods.

For the purpose of illustrating my invention I have chosen preferred forms of construction, but it is to be understood that I contemplate making other modifications, and therefore I do not desire to be limited to the exact structure shown and described, 105 but aim to cover all that which comes within the spirit and scope of the appended claims.

Having thus described my invention what I claim as new and desire to secure 110 by Letters Patent is:

1. A hair-waving tube comprising a tubular casing of relatively stiff material, rubber-cloth sheeting secured to the head end as an extension of the tube, and means 115 for securely fastening said extension so as to seal the tube adjacent the head.

2. A hair-waving tube comprising a tubular casing of relatively stiff material, rubber-cloth sheeting secured to the head end 120 as an extension of the tube, a thin absorbent sheet inside said extension, and means for securely fastening said extension so as to seal the tube adjacent the head.

3. A hair-waving tube comprising an inner absorbent paper tube and an intermediate cloth tube having an interposed layer of composition.

4. A hair-waving tube comprising an inner absorbent paper tube and an interme- 130

diate cloth tube having an interposed layer of composition, and an outer tubular casing having a relatively flexible non-absorbent head end extension with means for sealing 5 the same adjacent the head.

5. A hair-waving tube comprising a tubular casing of relatively stiff material, rubber cloth sheeting secured to the head end

as an extension of the tube, and means comprising a loop for securing a cord relatively 10 movable to said extension for securely fastening said extension so as to seal the tube adjacent the head.

In witness whereof, I have hereunto subscribed my name.

FELIX COUNE.
